H. M. SOMERVILLE:
WIRE SUSPENSION CLAMP,
APPLICATION FILED MAY 1, 1915.

UNITED STATES PATENT OFFICE.

HENRY M. SOMERVILLE, OF BLUEFIELD, WEST VIRGINIA.

WIRE-SUSPENSION CLAMP.

1,149,096.

Specification of Letters Patent.

Patented Aug. 3, 1915.

Application filed May 1, 1915. Serial No. 25,248.

To all whom it may concern:

Be it known that I, HENRY M. SOMERVILLE, a citizen of the United States, residing at Bluefield, in the county of Mercer 5 and State of West Virginia, have invented certain new and useful Improvements in Wire-Suspension Clamps, of which the following is a specification, reference being had to the accompanying drawings.

10 This invention relates to an improved wire suspension clamp and has for its primary object to provide a device of this character particularly designed for use upon electric power lines in cases where the 15 conducting wire exerts an upward strain or pull upon the clamp.

The invention has for a further and more particular object to provide a clamp of the above type including a body member provided with an integral wire engaging jaw 20 or extension having a curved lip, said body plate being provided with longitudinally extending arms on opposite sides of said jaw, whereby the clamp may be connected 25 between two series of insulators, and a wire clamping plate or jaw mounted upon said body plate for clamping engagement upon the wire.

It is a further general object of the invention to provide a clamping device for suspended conducting wires, which will effectively resist upward or downward strains of the wire thereon, said clamp, as a whole, being simple in its construction and capable of manufacture at comparatively 35 small cost.

With the above and other objects in view, my invention consists in the novel features of construction, combination, and arrangement of parts to be hereinafter more fully described, claimed, and illustrated in the accompanying drawing, in which,

Figure 1 is an elevation of a supporting structure such as is commonly used upon electric power lines, showing a conducting wire suspended therefrom by means of my improved clamp; Fig. 2 is an enlarged elevation of the clamp; and Fig. 3 is an edge view thereof.

Referring in detail to the drawing, 5 designates spaced horizontal beams which are fixed upon one or more vertical uprights 6. The electric conducting wire, indicated at 7, extends between the beams 5 and is suspended therefrom. For this purpose, a series of connected insulators 8 are

suitably attached to the upper beam 5. The wire suspension clamp embodies a cast metal plate, indicated at 9, which is provided upon its central portion with an integral laterally extending jaw 10 which projects from one side of the body plate. This jaw 10, at its point of juncture with the plate 9, is provided in its bottom face with a groove or seat, indicated at 11, to receive the conducting wire 7. It will be observed that the central portion of the plate 9 is of greatest width, and said plate, from each side of said central portion, is gradually reduced in width or attenuated 65 to produce the longitudinally projecting arms 12. The jaw 10 is relatively narrow and projects laterally from the body plate centrally of its widest portion. Upon this face of the plate and at each side of the jaw 10, the curved or arcuate concavo-convex lips 13 are integrally formed, the concave faces of said lips being downwardly disposed. These lips, in effect, provide continuations of the wire receiving channel or 70 groove 11 in the bottom face of the jaw 10 and the conducting wire extends upwardly upon said curved lips from each side of said jaw.

14 designates the movable wire clamping 75 jaw provided with the wire receiving seat 15 and a curved terminal lip 16 which is adapted to be engaged through an opening formed in the body plate 9 of the clamp. The jaws 10 and 14 are provided with openings 80 to receive the clamping bolt 17 upon one end of which the nut 18 is threaded.

The longitudinally projecting arms 12 are provided with terminal loops or eyes 19 and these arms are preferably reinforced by 85 the laterally extending flanges 20 which are formed upon their longitudinal edges.

It will be understood that, after the upwardly projecting arm 12 of the clamp has been attached to the hook of the lower one 100 of the series of insulators 8, the conducting wire 7 is securely clamped between the jaws 10 and 14. The downwardly extending arm 12 of the clamp is connected to the upper end of a second series of insulators, 105 indicated at 21, the lower insulator in said series being suitably attached to the lower beam 5 of the supporting structure. As above stated, the conducting wire extends on an upward inclination from the center 110 of the clamp and upon the curved lips 13. It will be apparent that, when the wire

- clamp has been arranged between the two series of insulators 8 and 21 and the wire secured therein in the manner above stated, said wire will be held in place with respect to the supporting structure and upward or downward pulls or strains resisted by the clamping device, wherein the wire is held. It is obvious, of course, that, if desired, the lower series of insulators 21 may be eliminated when it is not possible or convenient to employ the lower beam or bar 5, and a suitable weight connected to the lower arm of the clamp, or said arm tied down to any convenient fixed or stationary object. It will thus be manifest that I have devised a very simple form of clamping device which will not only hold the wire against downward movement when suspended in the supporting structure, but also afford means for eliminating the upward movement of said wire when the strain or pull of the same is in an upward direction.

From the foregoing description, taken in connection with the accompanying drawings the construction, manner of operation, and several advantages of the device will be clearly and fully understood. It will, of course, be obvious that the clamp may be made in various sizes and that the mounting and arrangement of the movable clamping jaw plate may also be considerably modified. The form and proportion of the several structural features of the clamp body can also be greatly varied in order to adapt the clamp to certain conditions, and I, therefore, reserve the privilege of resorting to

all such legitimate modifications as may be fairly embodied within the spirit and scope of the invention as claimed.

Having thus fully described my invention, what I desire to claim and secure by Letters Patent is:—

1. A wire suspension clamp of the character described including a body plate having a relatively wide medial portion and oppositely projecting, relatively narrow, longitudinally extending arms terminating in loops or eyes, and wire clamping means on one side of the central portion of the body plate. 50

2. A wire suspension clamp of the character described including a body plate having a relatively wide medial portion provided upon one side and at the center thereof with a laterally projecting jaw and also with longitudinally curved wire receiving lips extending from the opposite edges of the jaw to the outer edges of the body plate, a movable wire clamping jaw mounted at one of its ends in said body plate and opposed to said stationary jaw, and relatively narrow, longitudinally projecting arms integrally formed with the body plate and extending in opposite directions with respect to the center thereof, and said arms terminating in attaching loops. 60 65

In testimony whereof I hereunto affix my signature in the presence of two witnesses.

HENRY M. SOMERVILLE.
